WILSON BRAGG, OF CONNERSVILLE, INDIANA.

Letters Patent No. 83,358, dated October 27, 1868.

IMPROVED AUTOMATIC CAR-COUPING.

The Schedule referred to in these Letters Patent and making part of the same.

To all whom it may concern:

Be it known that I, WILSON BRAGG, of Connersville, Fayette county, Indiana, have invented a new and useful Improvement in Car-Couplings; and I do hereby declare the following to be a full, clear, and exact description thereof, reference being had to the accompanying drawings, making part of this specification.

My invention relates to that class of automatic car-couplings in which the pin is held in an elevated position by means of a sliding block, which, when forced back into the draw-head by the entering-link, permits the pin to engage therewith; and my improvement consists in connecting the pin and sliding block with a chain, in such a manner that when the pin is elevated, the block will be drawn out towards the mouth of the draw-head, said chain also serving to force the pin down into the link with a positive movement, as soon as the sliding block is pressed back in the draw-head.

In the accompanying drawings—

Figure 1 is a longitudinal section of my improved "car-coupling," with a link in position within the draw-head.

Figure 2 is a similar section, showing the link as about to enter the draw-head.

Figure 3 is a diagram, showing the pin in elevation and the coupling-link in section.

A represents a draw-head, having the customary flaring mouth *a*, and a longitudinal chamber, B, for the reception of the sliding block C, which plays freely within said chamber. The forward end of this block has a recess, C, into which the end of the link D fits, and the top of said block is provided with a longitudinal groove, C', to the bottom of which is attached one end of a chain or other flexible connection, E, whose other end is secured to the top of a peculiarly-constructed pin, F. The upper and longest portion of this pin is oblong in its horizontal section, while its lower end is diminished in size, so as to form a stem, G, which is adapted to enter an aperture, *a'*, in the bottom of the draw-head.

The enlarged portion of the pin F plays within a suitable bearing, *a'*, in the boss A', which is cast on the upper side of the draw-head, and this boss is provided with a channel, H, for the passage of the chain E.

Where the stem G unites with the pin F, there are formed two shoulders *ff'*, whose office will be hereafter described.

The inner and closed end of the chamber B is provided with an elastic cushion, I, which prevents too great a concussion when the sliding block C is forced back by the entering-link D.

My car-coupling is operated in the following manner:

As shown in fig. 1, the pin F is engaged with the link D in the same way it would be when the cars are coupled together, and should it be desired to disconnect them, it can be effected by simply pulling upon the chain E, which act not only elevates the pin, so as to disengage it from the link, but it also draws the sliding block C forward, and thereby ejects the link from the draw-head. As soon as the link has been expelled from the draw-head, the pin is allowed to drop, and rest upon the top of the sliding block, as seen in fig. 2, and when it is desired to couple the cars, the entering end of the link strikes within the recess *c* of the sliding block, and forces it back into the draw-head, the pin F falling, and passing through said link into the aperture *a'*, the moment the sliding block has travelled a sufficient distance. When the link is resting in the draw-head, the shoulders *ff'* of the pin bear upon the top of the link, and maintain it in a horizontal position, so that it will readily enter the draw-head of an approaching car.

Although the tendency of the pin is to hold the link in a horizontal position, yet the provision of the rounded stem G permits said link to play about within the draw-head sufficiently to accommodate itself to the oscillations of the car.

The upper portion of the pin being oblong in its horizontal section, prevents its turning in the draw-head, and thus insures the shoulders of the same bearing upon the link in a proper manner.

The pin being attached to the sliding block, it is compelled to descend with a positive movement, and there is no danger of its being jolted out of the draw-head by the vibrations of the car.

I claim herein as new, and of my invention—

The combination of the chain E, sliding block C, and coupling-pin F, substantially as and for the purposes specified.

In testimony of which invention, I hereunto set my hand.
